(57) **CLAIM**

The ornamental design for a storage rack with removable pegs, as shown and described.

DESCRIPTION

FIG. 1 is a front perspective view of my design;
FIG. 2 is front view of the embodiment shown in FIG. 1;
FIG. 3 is a bottom view of the embodiment shown in FIG. 1;
FIG. 4 is a side view of the embodiment shown in FIG. 1;
FIG. 5 is a top plan view of the embodiment shown in FIG. 1;
FIG. 6 is a rear view of the embodiment shown in FIG. 1; and,
FIG. 7 is a top, front perspective view of the embodiments shown in FIG. 1.

The broken lines used in FIG. 1 of the drawings disclosure are for illustrative purposes only and form no part of the claimed design.
